[57] CLAIM

The ornamental design for a material handling transport tray or the like, substantially as shown and described.

DESCRIPTION

FIG. 1 is a perspective view of a material handling transport tray or the like showing my new design;

FIG. 2 is a top plan view thereof;

FIG. 3 is a bottom plan view thereof;

FIG. 4 is a side elevational view;

FIG. 5 is an end elevational;

FIG. 6 is an end elevational view showing the end opposite that seen in FIG. 5; and

FIG. 7 is a side elevational view showing the side opposite that seen in FIG. 4.
